UNITED STATES PATENT OFFICE.

CHARLES C. MORRISON, OF HUNTINGTON, NEW YORK, ASSIGNOR TO PARK & TILFORD.

DESIGN FOR A PERFUME BOTTLE.

Application filed May 8, 1926. Serial No. 17,618. Term of patent 14 years.

To all whom it may concern:

Be it known that CHARLES C. MORRISON, a citizen of the United States, residing at Huntington, Suffolk County, State of New York, has invented a new, original, and ornamental Design for a Perfume Bottle, of which the following is a specification, reference being had to the accompanying drawings, forming part thereof.

I claim:

The ornamental design for a perfume bottle as shown.

In testimony whereof, I have hereunto affixed my hand this 3rd day of May, 1926.

CHARLES C. MORRISON.
